(57) **CLAIM**

The ornamental design for a kitchen tool, as shown and described.

DESCRIPTION

FIG. 1 is a front perspective view of a fragmented turner forming a kitchen tool, showing our new design; FIG. 2 is a fragmented top plan view thereof; FIG. 3 is a fragmented bottom plan view thereof; FIG. 4 is a fragmented left side elevational view thereof; FIG. 5 is a fragmented right side elevational view thereof; FIG. 6 is a fragmented front elevational view thereof; and, FIG. 7 is a fragmented rear elevational view thereof.

The broken line drawings of a handle of a turner in FIG. 1 are for illustrative purposes only and form no part of the claimed design.
